UNITED STATES PATENT OFFICE.

PHILIPP GOLDMANN, OF NEW YORK, N. Y.

CAP.

1,113,777.

Specification of Letters Patent.

Patented Oct. 13, 1914.

Application filed November 17, 1913. Serial No. 801,397.

To all whom it may concern:

Be it known that I, PHILIPP GOLDMANN, a citizen of the United States, residing at New York, county of New York, State of New York, have invented new and useful Improvements in Caps, of which the following is a specification.

This invention relates to a series of spring stiffening devices which are adapted for insertion into the inner portion of a cap to prevent the crown from collapsing.

The invention is essentially designed for caps usually worn by militiamen, policemen or conductors, and it includes means whereby the crown of the cap can be lowered along a suitable portion thereof so that the cap can be converted into an ordinary shape and worn at any time.

The spring devices consist of a series of 20 spring wire members each member having a double row of convolutions, swingingly mounted on a springy annular wire member arranged in the interior of the crown of the cap. The lower ends of the convoluted 25 wire members when normally in place are engaged by catches attached to the cap, thus supporting the annular wire member and keeping the crown in shape. The catch members are mounted on a springy wire member which in connection with the upper 30 wire member can be adjusted to different shaped or sized hats. When it is desired to turn the crown downward the convoluted members can be unhooked from the catches 35 and swung out of the way into the upper portion of the crown, the upper portion of the crown can then be moved downward and the cap then used for ordinary purposes.

The novel features of the invention are 40 more fully described in the following specification and claims and illustrated in the accompanying drawing in which:

Figure 1 represents a sectional side elevation of a cap embodying this invention. 45 Fig. 2 is a side elevation showing the stiffening devices spread apart. Fig. 3 is a perspective view of a catch member. Fig. 4 is a side elevation showing a portion of the haircloth stiffener.

50 In this drawing is shown a cap consisting of a crown *a* having a lining *b* formed of stiff flexible material such as buckram or hair cloth and secured at *c* to the inner upper portion of the crown. The lower end of this 55 piece of cloth sets against the inner portion of the body of the crown. This stiff cloth

has a backing of silk or other fabric *e* turned over the top portion of the cloth and stitched at *f* to the stiff cloth. When the stiff cloth is arranged in the crown of the cap the fabric *e* extends below the line of the cloth, and is secured at *g* to the lower portion of the crown. The lower portion of the crown has secured to it a stiff band *h*. The upper end of this band is adjacent to the end of the stiff cloth *c* but does not quite touch the same so that the portions between the band and the cloth *b* with the strip of fabric *e*, will constitute a hinge joint along which the upper portion of the crown can 70 be collapsed.

It will be seen that by reason of the method of fastening the cloth *b* to the upper portion of the crown and then bending it at right angles down the side as shown it forms 75 a flexible rim to prevent wrinkling and retain the shape of the crown.

In order to prevent the crown from collapsing when in use a device consisting of a series of convoluted spring stiffening members *j* is inserted into the crown of the cap. The spring members are swingingly mounted on a springy annular wire member *k* positioned in the top of the crown. The ends of the member *k* are jointed together 80 by means of a coupling *m* having a set screw *n* for holding the ends of the annular member together. The annular member can thus be adjusted to any dimension, and snugly fitted into the crown of the cap. 85

In the lower portion of the crown is arranged a second annular wire member *o* having a coupling *p*, like the above mentioned coupling, for adjusting the member. On this member are slidably mounted a 90 series of catches *q*. Each catch can be attached at *r* to the inner lower portion of the crown. The catch is formed of a single sheet of thin metal and it has a lip *s* to engage the lower portion of a convoluted 100 member. Each member has a double row of convolutions as shown and the members are spaced in the crown of the cap so that the front portion where the forehead rests will be free of the springy devices. The 105 catches at the lower portion of the crown are normally covered by the sweat leather.

When it is desired to collapse the crown the convoluted members are disengaged from the catches and swung upwardly, the upper portion of the crown can then be telescoped into the lower portion with the flex- 110

ible portion above the band as the folding point. This joint is located approximately about the central portion of the crown so that the whole upper portion of the cap 5 will drop down when the convoluted stiffener braces are removed.

The interior stiffening devices can be marketed separately from the cap, and adjusted to conform to any shape or size of cap.

10 The stiff cloth *b* and the silk lining are gathered when sewed into the crown thus forming a pocket between the angle of the top and sides, for the wire member. In this form of construction the wire member is 15 retained in its position in the pocket by the drawing in of the stiffening member. The wire member shapes itself to conform to the curvature of the rim and bulging or undulation of the rim is avoided.

20 It should be understood that the whole upper portion of the cap above the band can be moved downward, hence when the cap is packed in a box for shipping, it will take up a small amount of space.

25 I claim:

1. A stiffening device for caps comprising an adjustable annular wire member, a series of convoluted wire members swingingly mounted on the annular wire member, 30 and a series of catches adapted for attachment to the interior of the cap to engage the convoluted members.

2. A stiffening device for caps comprising an adjustable annular wire member, a series 35 of double convoluted wire members swingingly mounted on the annular wire member, and a series of catches adapted for attachment to the interior of the cap to engage the convoluted members.

40 3. A stiffening device for caps comprising a pair of adjustable annular wire members, a series of convoluted wire members swingingly mounted on one of the annular wire members, and a series of catch members 45 mounted on the second annular wire member to engage the convoluted members.

4. In a cap the combination with the crown, of a pair of adjustable wire members positioned in the crown, a series of convoluted wire members swingingly mounted 50 on one of the annular wire members, each member having a double row of convolutions, and a series of catch members mounted on the second wire member for engagement with the convoluted members. 55

5. In a cap the combination with a crown, of a pair of adjustable wire members positioned in the crown, a series of convoluted wire members swingingly mounted on one 60 of the annular members, each member having a double row of convolutions, and a series of catch members, each formed of a single piece of metal slidingly mounted on the second wire member for engagement with the convoluted members. 65

6. A cap comprising a crown, a cloth stiffener secured to the upper interior portion of the crown and extending downwardly, a stiff band secured to the lower portion of the crown adjacent to the stiffener, said stiffener and the band being adapted in connection with the fabric of the crown to form a hinge joint so that the crown above the band can be collapsed. 70

7. A cap comprising a crown, a cloth stiffener secured to the upper interior portion of the crown and extending downwardly, a stiff band secured to the lower portion of the crown adjacent to the stiffener, said stiffener and the band being adapted in connection with the fabric of the crown to form a hinge joint so that the crown above the band can be collapsed, and stiffening devices positioned in the crown to normally prevent the crown from collapsing. 75 80 85

In testimony whereof I have hereunto set my hand in the presence of two subscribing witnesses.

PHILIPP GOLDMANN.
